US00D767988S

(12) **United States Design Patent** (10) Patent No.: **US D767,988 S**
(45) Date of Patent: ** Oct. 4, 2016

(54) **PACKING CASE FOR LOCK DEVICES**
(71) Applicant: **TAIWAN FU HSING INDUSTRIAL CO., LTD.**, Kaohsiung (TW)
(72) Inventors: **Wen-Fa Wu**, Kaohsiung (TW); **Chiao-Chin Lu**, Kaohsiung (TW)
(73) Assignee: **TAIWAN FU HSING INDUSTRIAL CO., LTD.**, Kaohsiung (TW)
(**) Term: **15 Years**
(21) Appl. No.: **29/531,623**
(22) Filed: **Jun. 28, 2015**
(30) **Foreign Application Priority Data**

May 12, 2015 (TW) 104302532

(57) **CLAIM**

The ornamental design for a packing case for lock devices, as shown and described.

DESCRIPTION

FIG. 1 is a front perspective view of a packing case for lock devices showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown represent unclaimed subject matter and form no part of the claimed design.
